Attns.

UNITED STATES PATENT OFFICE.

ISAAC M. GLICK, OF BOSTON, MASSACHUSETTS.

ANTITHEFT DEVICE.

Application filed January 17, 1923. Serial No. 613,129.

My invention relates to anti-theft devices and particularly but not exclusively to one for motor vehicles.

My invention will be best understood from 5 the following description when read in light of the accompanying drawings of one specific embodiment of my invention selected for illustrative purposes, while the scope of my invention will be more particularly pointed 10 out in the appended claims.

In the drawings:—

Fig. 1 shows an elevation of my invention applied to a motor vehicle;

Figs. 2 and 3 are sections respectively on 15 the lines 2—2 and 3—3 of Fig. 1;

Fig. 4 is a section on the line 4—4 of Fig. 3;

Fig. 5 shows a detail;

Fig. 6 is a wiring diagram; and

Fig. 7 shows a detail.

Referring to the drawings and to the preferred embodiment of my invention I have shown a motor vehicle windshield 1 to the stanchions 3 of which I secure a roller 25 curtain indicated in its entirety at 5 which may be drawn over the windshield so as to obstruct vision from the driver's seat.

Specifically at the upper end of the stanchions I secure brackets 7 which carry the 30 tubular casing 9 for the curtain. In the casing I mount a curtain roller 11 about which the curtain is adapted to be wound, the casing being provided with a longitudinally extending aperture 13 through which 35 the curtain extends.

In the submitted embodiment of my invention I have shown a curtain which comprises a plurality of spring steel bands 15. Carried by these bands I provide a plurality 40 of transversely positioned, closely adjacent slats 17 which preferably are formed of metal. The bands 15 are so formed that they tend when unrestrained to assume the shape of a flat spiral, that is, a shape similar to a clock spring. One end of each band is connected to the curtain and by this construction when the curtain is released the same will turn the roller and consequently will automatically roll up.

50 For guiding the curtain I secure to the stanchions 3, as for example by means of the rivets 19, channel shaped members 21 which on one side are formed with the slots 23 into which the ends of the slats project,

The guiding of the slats in this manner prevents the curtain from bulging under the influence of the bands 15.

In each channel member 21 I provide a flat strip 25 of metal or other suitable material which at its lower end rests upon the pins 27 carried by the walls of the channel member. Carried by each strip are a plurality of switches 29 each of which as will be understood by those skilled in the art is adapted to be operated by an associated 55 push button 30. I have shown three switches distributed along each strip 25 and between each switch and the back wall of the channel member 21 I have shown a compression 60 spring 31 these springs acting to hold the strip 65 yieldingly against the front wall of the channel member so as to close the slot 23 therein.

At the lower end of the curtain I provide 70 a curtain rod 33 which carries the handle 75 35 for manipulating the curtain. For locking the curtain in its lowermost position I provide a key controlled lock of known construction having a rotary key-receiving barrel 37, said lock having the oppositely extending bolts 39 which when the lock is turned enter the slots 23 and project under the bottom ends of the strips 25, the latter in this manner acting as keepers for the 80 bolts.

As shown herein the bolts 39 adjacent the barrel 37 of the lock are provided with racks 40 which mesh with a gear 40^a formed by providing the barrel 37 with teeth. As shown by Fig. 7 the respective racks 40 85 mesh with the gear 40^a at opposite sides of the latter so that turning of the barrel 90 will be effective to move the bolts 39 simultaneously in opposite directions.

For indicating tampering with the curtain I provide suitable alarms which, although they may be otherwise, as herein illustrated are of the audible type being exemplified by the electric bells 41 and 43, the former of which are located at opposite ends 95 of the curtain casing 9 as is indicated in Fig. 1, while the latter may be located in any inaccessible part of the vehicle to prevent tampering therewith.

As is indicated by Fig. 6 one terminal of the several switches 29 enclosed in each channel member 21 are connected in parallel by means of a wire 44 to one terminal

of the corresponding bell 41, the other terminal of the bell being grounded. The other terminals of the push buttons are connected to wires 45 which, by means of a circuit 47 which includes the bell 43, are placed in electrical communication with the discharge side of the ammeter 49 or in any other convenient way with a terminal of the battery 51 or other source of electro-motive force. Herein the battery has its other terminal grounded. As will be obvious closure of any of the push buttons will ring the bell on the corresponding side of the windshield and with it the bell 43. By use of a plurality of bells and switches I reduce to a minimum the possibility of so tampering with the mechanism that no alarm will be sounded.

In operation when the curtain is drawn to its lowermost position the lock is operated to cause the bolts 39 to extend under the lower end of the strips 25, and if it is attempted to force the curtain up the bolt 39 will cause one or both of the strips 25 to be pressed outwardly thereby causing one or more of the push buttons 30 to contact the outer walls of the channel members 21 and thereby closing one or more of the switches and actuating the alarm.

Although I have described for purposes of illustration one specific embodiment of my invention it is to be understood that I am not limited thereby to its particular mechanical details but that within the scope of my invention wide deviations may be made therefrom without departing from the spirit of my invention.

Claims:

1. An anti-theft device for vehicles having a windshield, comprising a curtain having a position in which it is operative to obstruct vision through said windshield, side guides for said curtain, a lock having a bolt for holding said curtain at the bottom of said side guides, an alarm, means including switch mechanism for actuating said alarm, and means carried by one of said side guides

and interposed in the path of said bolt for actuating said switch mechanism.

2. An anti-theft device for vehicles having a windshield comprising a curtain having a position in which it is operative to obstruct vision through said windshield, side guides for said curtain, an alarm switch mechanism carried by one of said side guides, a key-controlled lock having a movable bolt for holding said curtain in its operative position, and said switch mechanism comprising an actuating member constituting a keeper for said bolt whereby unauthorized movement of said curtain towards its inoperative position will actuate said switch mechanism.

3. An anti-theft device for vehicles having a windshield, comprising a curtain having a position in which it is operative to obstruct vision through said windshield, side guides for said curtain, an alarm, a switch in one of said side guides, a bolt for holding said curtain at the bottom of said side guides, and a resilient strip extending along one of said side guides in operative relation to said switch, whereby said bolt will contact said resilient strip and thereby actuate said switch when said curtain is raised without withdrawal of said bolt.

4. An anti-theft device for vehicles having a windshield, comprising a curtain having a position in which it is operative to obstruct vision through said windshield, side guides for said curtain, an alarm, a plurality of switches in one of said side guides, a bolt for holding said curtain at the bottom of said side guides, and a resilient strip extending along one of said side guides in operative relation to said switches, whereby said bolt will contact said resilient strip and thereby actuate one or more of said switches when said curtain is raised without withdrawal of said bolt.

In testimony whereof, I have signed my name to this specification.

ISAAC M. GLICK.
